UNITED STATES PATENT OFFICE.

GEORGE THEODORE LIM, OTHERWISE KNOWN AS GEORGE THEODORE LAM, OF VICTORIA, HONGKONG.

METHOD OF WEAVING.

Application filed April 2, 1925. Serial No. 20,313.

This invention relates to a new and novel method and process of binding, weaving and securing from unravelling the ends of reed, rattan or seagrass in the manufacture of the leg work of reed, rattan or seagrass chairs, rockers, settees, tables, desks, chaise longues, day beds, smoking stands, tea wagons or carts and other reed, rattan and seagrass furniture having legs.

10 This new process of weaving is known as "ringed and braced legwork."

With the preceding and other objects and advantages in mind, the invention consists in the novel construction and arrangement 15 of materials ad workmanship, to be herein-after explicitly referred to, claimed and illustrated in the accompanying drawings, in which:

20 Figure 1 is an elevation of a fragmentary portion of a furniture leg showing the first step in the method of securing the material thereto.

Figure 2 is a perspective view of the leg showing the novel ring formed thereon.

25 Figure 3 is an elevation showing the application of the brace material.

Figure 4 is a similar view of the completed work.

30 Figure 5 is a similar view of the completed work with the woven material cut longitudinally with respect to the leg to illustrate the compactness and substantial manner in which the brace material holds the woven material.

35 Figure 6 is a view of a slightly modified method.

Figure 7 is a view of the form shown in Figure 6 in its completed state.

40 Figure 8 is a view similar to Figure 5 to illustrate that the same substantial and effectual manner of holding the woven material is present in the modified form.

45 Referring to the drawings in detail the numeral 1 indicates a leg of such articles as mentioned above, and secured to the end 2 of said leg through the medium of a smooth round headed foot nail 3 is an end covering 4 which is formed from a number of elongated strips indicated by the reference numeral 5.

50 At the start of the winding process around the leg of such articles, the commencing end of the winding material (whether reed, rattan peel, rattan core or seagrass) is first inserted into a recess 7 formed adjacent the

end of the rattan leg 1 and then nailed firmly in said recess with a brass nail 8 as shown in Fig. 1 of the drawings.

The winding material 6 is then wound round the leg a few turns in order to allow the insertion of about nine to twelve round rattan core sticks 9, six inches in length, from which the ring 10 is braided. The ring 10 is formed by intertwining or interlacing of the said round rattan core sticks 9 around 65 the end of the leg in the manner shown in Fig. 2.

As soon as this ring 10 is completed the actual winding process with winding material 6 around the leg commences and simultaneously, brace elements 11, five to six 70 in number, are inserted between the ring 10 and some windings of the material 6 as shown in Figure 3.

The brace elements 11 having been inserted and bent into position as shown and the winding of the winding material around the leg continues and passes alternately over and under the braces above referred to, until the ends of the braces are reached, by which 75 it will be seen how these braces 11 in turn interlace the winding material 6 all around the leg 1, whereby unravelling or unwinding is rendered impossible. The protuding ends of the sticks 9 are disposed between the winding material 6 and the leg 1. The winding material then continues on its course around the leg until the winding process of the winding material is completed and the free ends of said material are inserted 80 between the leg and the lower winds or turns of the material for securing the same.

85 For the purpose of demonstration as to how effectively unravelling or unwinding is rendered impossible, a cut 12 is made 90 through the winding material after completion of this leg-work as shown in Fig. 5, whereby it is shown that in spite of this cut, the winding material is held intact by the braces 11.

95 When the protruding ends 13 of the "ring" 10 are used as braces as shown in Fig. 6 the same result is obtained as when the braces 6 are inserted separately as illustrated in Fig. 3, namely the interlacing of the winding material between and about the said braces 13.

105 The effect of holding the winding material by the braces 13 is the same in the modified form, as when a cut as at 14 is made 110

through the winding material as shown in Fig. 8, it is again obvious that in spite of this cut, the winding material is held intact.

5 In conclusion it is hereby emphasized that whether the ring 10 and separate braces 11 are used to interlace the winding material or whether the protruding ends 13 thereof are used as braces in continuity with the 10 ring are employed the same result is aimed at and obtained, namely, prevention of unravelling.

What I claim is:

15 1. The process of binding, weaving and securing from unravelling the ends of reed, rattan or seagrass in the manufacture of leg work for furniture, by forming a recess in the leg, securing one end of a piece of reed therein with a nail, winding the reed about 20 the leg several turns inserting flexible sticks in the turns and forming a ring by intertwining and interlacing the sticks within

themselves and weaving reed about the ring and leg in the manner as described.

2. A method of weaving material about the legs of furniture by forming a recess in the leg adjacent one end, securing one end of a winding material therein, winding said material about the leg for several turns, inserting rattan sticks in the turns and forming a braided ring therefrom adjacent said end of said leg, again winding said material and inserting brace elements between the last mentioned windings and the ring, disposing said elements upon opposite sides and parallel with the leg, thence winding said material alternately over and under said brace elements and securing the free end of said material between the windings and leg respectively.

Signed at Hongkong on this 10th day of November, 1924.

GEO THEO. LIM,
Otherwise known as Geo. Theo. Lam.
